(57) **CLAIM**

We claim the ornamental design for a cartridge, as shown and described.

DESCRIPTION

FIG. 1 is an isometric view of a cartridge.

FIG. 2 is a right side view of the cartridge of FIG. 1.

FIG. 3 is a left side view of the cartridge of FIG. 1.

FIG. 4 is a top view of the cartridge of FIG. 1.

FIG. 5 is a bottom view of the cartridge of FIG. 1.

FIG. 6 is a rear view of the cartridge of FIG. 1.

FIG. 7 is a front view of the cartridge of FIG. 1.

FIG. 8 is an off-angle view of the underside of the cartridge of FIG. 1; and,

FIG. 9 is another off-angle view of the underside of the cartridge of FIG. 1.

Stipple shading is used in the accompanying FIGS. 1-9 to convey surface contouring and is not indicative of any particular texture, coloring, or opacity/transparency.

Dash-dot-dash boundary lines are used herein to indicate a transition from claimed subject matter to unclaimed environmental structure, as evidenced by the absence of shading within the boundary shape and the presence of shading outside of the boundary shape. See, for example, the dash-dot-dash boundaries around the “illumina®”, “INSERT” and “1” text, which are disclaimed in FIGS. 1 and 4.

1 Claim, 9 Drawing Sheets
